ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

SLIDING SUPPORT FOR VISIBLE INDEX TRAYS

Application filed June 27, 1930. Serial No. 464,163.

This invention relates to a support for visible index trays by which the tray may be slid into and out of a cabinet and which shall be so related to the tray as to permit it to be 5 fully occupied by cards without sacrifice of any of its space. More particularly, the invention seeks to provide a sliding support with which the tray itself is telescopically engaged so that the tray may have sliding 10 movement with respect to the support and be drawn into such a position with respect thereto as to expose the tray and its cards for normal use. A further object of the invention is to provide means on the tray support 15 for positively lifting the top card from its overlying relation to the index cards when the tray is fully retracted, the top card being returned to its overlying position when the tray and support are returned into the cabinet. A further object of the invention is to 20 provide actuating means for the top card which may be removed from engagement with the coacting means on the tray support so as to permit the tray to be withdrawn 25 bodily from the tray support without further operation.

The invention will be described in detail in connection with the illustrated embodiment shown in the drawings, wherein:

20 Figure 1 is a fragmentary view in side elevation of a cabinet showing a tray and improved tray support withdrawn therefrom and the top card elevated by the coacting means.

25 Figure 2 is a view of a fragment of the tray and support shown in Figure 1, the cabinet being illustrated in horizontal section to show how the tray support is slidably engaged therewith, the section being taken on the line 2-2 of Figure 3 and looking in the direction of the arrows.

Figure 3 is a view in side elevation of the improved tray support and tray, the near wall of the cabinet being broken away in the 45 interest of clearness and the tray being only partly retracted.

Figure 4 is a view similar to Figure 3 showing the tray fully retracted.

50 Figure 5 is a fragmentary view in vertical section through the cabinet showing the en-

gagement therewith of the tray support and taken on the plane indicated by the line 5-5 of Figure 4 and looking in the direction of the arrows.

The cabinet *a* may have mounted therein suitable opposed ways shown in Figure 5 as consisting of stamped and formed pieces *b* with grooves *b'* to receive slidably supporting pins *c* carried by the tray support which will be described hereinafter. One or both 55 of the pins *c* as shown at the right-hand side of Figure 2 may be retractile for disengagement with the ways *b* of the cabinet so that the tray support may be demounted. A finger pull *c'* at the inner end of the pin *c* facilitates its convenient operation. The tray support is of simple and inexpensive 60 construction when made in accordance with the illustrated embodiment and may comprise a false tray having a transverse bottom *d* and channeled flanges *d'* along its opposite side edges. These channel flanges are of such shape and dimensions as to receive slidably therein the card tray *e* so that the card tray is in sliding and telescopic relation to the tray support *d*. So far as the construction 65 has been described it will be apparent that with any suitable means to prevent the tray *e* from being wholly withdrawn from the tray support *d* when drawn out of the 70 cabinet a simple and inexpensive tray support is afforded whereby the tray may be slid into the cabinet through the sliding engagement of the pins *c* with the ways *b'*.

In accordance with the further object of the 75 invention a simple and effective stop for the tray is provided to prevent its complete withdrawal while at the same time permitting the tray to be used in its full length 80 with the usual index cards therein and without requiring any standard type of tray to 85 be modified in construction. At the inner end of the tray there is provided as usual a pivotal support for a top card *f*, the pintle therefor being indicated at *f'*. Spaced from the pintle *f'* and carried on the top card *f* are outwardly extending pins *f*² which in the 90 illustrated embodiment are made as independent sections normally urged into their extended position by a spring *g* operatively 95 100

interposed between the proximate ends thereof. Each of the pins f^2 may be formed with a finger piece f^3 whereby they may conveniently be retracted against the pressure 5 of the spring g for the purpose to be pointed out hereinafter.

On the channeled flanges d' of the tray support d are secured cam stops h preferably provided with inclined cam surfaces h' engageable by the pins f^2 when the tray is drawn outwardly, these cam surfaces terminating preferably in vertically disposed edges h^2 which serve as positive stops for the pins f^2 preventing their further travel with 15 respect to the tray support d .

From the description given it will be apparent with reference to Figures 3 and 4 that when the tray is grasped by the usual finger pull e' it will be withdrawn from the cabinet 20 together with the slideable tray support d . When the pins c of the tray support reach the forward ends of the ways b' further movement will be positively checked by engagement with the cabinet. Continued 25 movement of the tray e in the channel flanges d' will bring the pins f^2 of the top card f into engagement with the cam surfaces h' of the stops h . As the pins f^2 ride up these cam surfaces it will be evident that the top 30 card will be swung upwardly about the pivotal f' until the pins f^2 engage the vertical stops h^2 at which time further movement of the tray e and the top card f with respect to the tray support d is positively arrested. 35 At this time, as shown in Figure 3, the top card has been swung away from the index cards which it normally overlies and the full length of the tray is exposed to view for 40 manipulation of the cards therein. The tray with the tray support may be dropped to an angular position moving about the pins c .

If it is desired to remove the tray from the card support or to engage a tray therewith the pins f^2 can be retracted against the action 45 of the spring g by manipulation of the finger pieces f^3 so that the ends of the pins will clear the cam stops h and the tray e by reason of its telescopic engagement with the support d can be pulled out until it is disengaged therefrom. 50

When the tray is to be returned into the cabinet its movement in the tray support will permit the pins f^2 to ride down the cam surfaces h' until the top card f is in normal position, continued movement of the tray and tray support carrying the parts into the cabinet. 55

The entire construction is very simple, easy to assemble and disassemble, permits the introduction or removal of the tray supports from a cabinet and permits the introduction or removal of trays from the tray supports. Details of construction by which equivalent results are obtained may be changed readily 60 as will be apparent to any skilled mechanic 65

without departing from the spirit of the invention.

What I claim is:

1. A support for a visible index tray comprising a unitary member having channels 7 to receive the tray slidably and telescopically, a top card hinged to the tray, a cam stop carried by the support and means on the top card to engage the cam stop when the tray is moved in one direction with respect to the support whereby the top card is swung upwardly and further relative movement of the tray and support positively checked. 71

2. A support for a visible index tray comprising a member having means to receive a tray telescopically and slidably, a top card hinged on the tray, pins carried by the top card spaced from the hinged support therefor and overlying the tray support, cam stops carried by the tray support and engageable 80 by said pins upon movement of the tray with respect to the support, whereby the top card is swung upwardly and further movement of the tray positively arrested. 85

3. A support for a visible index tray comprising a member having means to receive a tray telescopically and slidably, a top card hinged on the tray, pins carried by the top card spaced from the hinged support therefor and overlying the tray support, cam stops 90 carried by the tray support and engageable by said pins upon movement of the tray with respect to the support, whereby the top card is swung upwardly and further movement of the tray positively arrested, and means to retract said pins from the path of the cam stops. 95

4. In combination with a cabinet having opposed ways, a support for a visible index tray comprising a unitary false tray section 10 having channels at its opposite edges to receive a tray in telescopic sliding relationship thereto, means carried with the false tray section in sliding engagement with the ways to support it in the cabinet, said means constituting a pivotal connection whereby when the false tray section is retracted from the cabinet it may be swung downwardly from the horizontal, and coacting means carried by the false tray section and the tray to limit 11 relative sliding movement therebetween, whereby the channels hold the tray against relative angular movement with respect to the false tray section. 111

This specification signed this 24th day of 120 June A. D. 1930.

ROLAND A. FURLONG.
